(Continued)

Primary Examiner — Susan E Krakower(74) *Attorney, Agent, or Firm* — Thomas & Karceski, P.C.(57) **CLAIM**

The ornamental design for a pedal exerciser, as shown and described.

DESCRIPTION

FIG. 1 is a perspective view of a pedal exerciser showing my new design; and,

FIG. 2 is a right side view thereof.

The broken lines show environmental elements of the pedal exerciser which form no part of the claimed design.
